(57) **CLAIM**

The ornamental design for a stand for musical instrument as shown and described.

DESCRIPTION

FIG. 1 is a top, left, front perspective view of a stand for musical instrument, showing my new design;

FIG. 2 is a top, right, rear perspective view thereof;

FIG. 3 is a left, front, perspective view thereof;

FIG. 4 is a left, rear, perspective view thereof;

FIG. 5 is a left side elevational view of the left leg of the stand for musical instrument, the remainder of the design shown removed for ease of illustration; the right side elevational view of the right leg being a mirror image thereof; FIG. 6 is a right side elevational view of the left leg of the stand for musical instrument, the remainder of the design shown removed for ease of illustration; the left side elevational view of the right leg being a mirror image thereof; FIG. 7 is a top, left, front perspective view of the left leg of the stand for musical instrument; the remainder of the design shown removed for ease of illustration; the top, right, front perspective view of the right leg being a mirror image thereof; and,

FIG. 8 is a top, right, rear perspective view of the left leg of the stand for musical instrument, the remainder of the design shown removed for ease of illustration; the top, left, rear perspective view of the right leg being a mirror image thereof.

The dash-dot broken lines in FIGS. 1 and 2 depict unclaimed environmental subject matter. The portions of the stand shown in dashed broken lines on FIGS. 1-7 form no part of the claimed design.

1 Claim, 7 Drawing Sheets
